US00D880912S

(12) United States Design Patent (10) Patent No.: US D880,912 S
(45) Date of Patent: * Apr. 14, 2020

(54) TABLE

(71) Applicant: NATUZZI S.p.A., Santeramo in Colle (Bari) (IT)

(72) Inventors: Ellen Bernhardt, Milan (IT); Paola Vella, Milan (IT)

(73) Assignee: Natuzzi S.p.A., Santeramo in Colle (Bari) (IT)

() Term: 15 Years

(21) Appl. No.: 29/633,690

(22) Filed: Jan. 15, 2018

(30) Foreign Application Priority Data

Jul. 13, 2017 (EM) 004101210-0041

(51) LOC (12) Cl. 06-03

(52) U.S. Cl.

USPC D6/692

(58) Field of Classification Search

USPC D6/349, 641, 642, 685, 686, 692, D6/692.1-692.6

CPC A47B 7/00; A47B 13/00; A47B 13/02; A47B 13/04; A47B 13/06; A47B 13/08; A47B 13/12; A47B 17/00; A47B 21/00; A47B 2200/0001; A47B 2200/0011; A47B 2200/0002
